United States Patent Office

Des. 197,594
Patented Mar. 3, 1964

197,594

BRUSH HOLDER

Bertrand N. Trombley, Bloomfield Hills, Mich., assignor to Harper J. Ransburg Company, Inc., a corporation of Indiana

Filed July 2, 1963, Ser. No. 75,630

Term of patent 14 years

(Cl. D9—2)

Fig. 3.

Fig. 4.

Fig. 5.

Fig. 6.

FIG. 1 is a front elevation of a brush holder embodying, my new design;

FIG. 2 is a side elevation thereof;

FIG. 3 is a plan view thereof;

FIG. 4 is a rear elevation thereof;

FIG. 5 is a vertical section taken on the line 5—5 of FIG. 1; and

FIG. 6 is a vertical section taken on the line 6—6 of FIG. 2.

The side opposite the side shown in FIG. 2 has the same design appearance as that illustrated in FIG. 2.

I claim:

The ornamental design for a brush holder, as shown and described.
